UNITED STATES PATENT OFFICE.

FLOYD E. PERKINS, OF BAUDETTE, MINNESOTA.

ELECTRIC MAIL-CARRIER.

1,250,002.

Specification of Letters Patent. Patented Dec. 11, 1917.

Application filed April 11, 1917. Serial No. 161,231.

To all whom it may concern:

Be it known that I, FLOYD E. PERKINS, a citizen of the United States, residing at Baudette, in the county of Beltrami and 5 State of Minnesota, have invented new and useful Improvements in Electric Mail-Carriers, of which the following is a specification.

This invention pertains to improvements 10 in aerial transportation means, and has particular reference to an aerial device for conveying mail.

In carrying out this invention it is my purpose to provide a carrier which will expeditiously and economically convey mail matter and other articles from place to place.

It is my further intention to embody in such a device features insuring adequate 20 protection from weather and from intermeddling by unauthorized persons for the mechanism of the device and articles carried thereby.

I also propose to provide in such a device 25 a more efficient combination and disposition of parts, and an improved means for controlling the action of the device.

With these and other objects in view the invention consists in the construction, combination and arrangement of parts shown 30 in the accompanying drawings and described in the specification and claims below.

In the drawings,

Figure 1 shows a carrier in position on 35 the track.

Fig. 2 is a side elevation of portions of the carrier with the casing removed.

Fig. 3 shows details of the mechanism.

Fig. 4 is another view of the carrier.

40 Referring to the drawings more particularly, 1 represents the carrier which is adapted for self-propulsion upon a track rail 2 maintained by suitable supporting structures 3 at an elevation above the earth's surface. The track rail 2 is similar to those commonly used for such purposes with the exception that the upper or wheel engaging portion of the rail is so formed as to constitute an inverted V when viewed in section.

45 Adjacent or over the rail 2 and extending in parallelism therewith is a suitable conductor or trolley wire 4 for conveying electric current to the carrier and which is supported by but insulated from arcuate arms 4' properly secured to a vertical extension of the supporting structures 3 carrying the track

5 rail. The supporting structures are further utilized for maintaining in position a second insulated conductor 5 whereby telephonic or telegraphic communication between different stations along the track way may be facilitated.

As viewed exteriorly, the carrier comprises a casing 7 having a downwardly extended portion 8 which may be curved under to partially embrace the track rail 2 and is provided at the lower extremity with a means for attaching a load to the carrier. This means consists in the present instance of a hook 9 having attached thereto a link 70 connected at the lower end to an air and water-tight receptacle 6 wherein mail and other objects may be conveniently placed. The receptacle 6 is preferably constructed of sheet metal and is provided with a cover 75 for convenient access to the interior and with a lock 6' of any approved design for securing the cover in closed position when desired. As viewed exteriorly, the case of the carrier has upon one side a protrusion 10 comprising a separately formed receptacle 80 of metal affixed to the main body of the case in any acceptable manner, as for instance, by lugs on the receptacle 6, formed with openings for registration with similar openings formed in the casing for the passage of retaining bolts, whereby the receptacle may be drawn into close contact with the casing 85 to form an air and water-tight joint therewith.

90 Within the hollow formed in the casing 7 are alined wheels 12 keyed or otherwise properly fastened to shafts 13 extending transversely of the carrier, properly journaled in the casing, and provided with prolongations extending through the upper receptacle affixed to the side of the casing. The horizontal portion of the casing adapted to be located immediately above the track rail is formed with elongated openings, and the wheels are of such size and so disposed in the casing that a circumferential portion of each wheel will extend through the respective opening for engagement with the track rail. To prevent lateral displacement 100 of the wheels from the track rail I form the treads with a peripheral groove 13 substantially V-shaped and adapted to engage the similarly shaped upper portion of the track rail 2. Within the receptacle 10 extending longitudinally thereof and properly journaled in bearings which may be at-

tached either to the receptacle or to the main casing is a drive shaft 14 terminating at each end in juxtaposition to the respective shaft 13 of one of the wheels 12.

5 A conical clutch member 15 is mounted upon each extremity of the drive shaft for engagement with a similar clutch member 15' keyed or otherwise secured to the respective wheel shaft 13 for rotation of the 10 wheel.

When desired, I may affix the latter clutch member directly to the hub of a wheel 12 in which instance a suitable opening is formed in the casing to permit engagement 15 with the corresponding clutch member 15 of the drive shaft. A key is inserted in each drive shaft for engagement with a slot formed interiorly of the clutch member 15, thereby insuring rotation of the clutch 20 member with the shaft, and at the same time permitting a sliding movement longitudinally of the shaft, whereby the respective clutches may be engaged and disengaged. For effecting such engagement and disengagement, a suitable hand lever 16' is provided attached to a pivotal support 16 affixed interiorly to the case 7, and extending outwardly through an elongated opening 7' formed in the case. A portion of 25 the hand lever adjacent the pivotal support 16 is expanded laterally in the plane of movement of the lever to constitute a plate formed with openings 17 on either side of the median line of the lever. These openings 30 are adapted for engagement by the extremities of links 18, whereby one of the clutch members 15 will be engaged for rotation of the respective wheel in one position of the hand lever and the other clutch 35 member will be engaged for reverse rotation of the respective wheel 12 in the other position of the hand lever, while in the neutral or intermediate position, both clutch members will be disengaged.

40 In the present instance, the outer extremity of each link is provided with a means for actuating the respective clutch member 15, comprising an annular portion 19 constituting the extremity of each link, embracing a 45 cylindrical prolongation 20 of the clutch member concentrically of the drive shaft, and adapted to engage suitable shoulders formed on said cylindrical extension.

For propulsion of the carrier, a power 50 device is provided, here shown as an electric motor 21 mounted within the casing 7. Motor 21 is disposed for rotation of the armature 22 in a plane parallel with the path of movement of the carrier, the armature 55 thereby constituting a gyroscopic element adapted to maintain the equilibrium of the carrier. A suitable means is provided for transferring power from the armature shaft 23 of the motor to the drive shaft 14, comprising in this instance a beveled gear 25

keyed or otherwise secured to the armature shaft 23 and a beveled gear 24 similarly affixed to the drive shaft 14, and a counter-shaft 26 provided at one extremity with a beveled gear engaging the motor gear 25, 70 and at the other extremity with a beveled gear engaging the drive shaft gear 24. Counter-shaft 26 is journaled in a supporting member 24', the extremities of which constitute journals for the drive shaft, and 75 which is properly secured to the wall of the case.

For supplying current to the motor 21 from the trolley wire 4 a trolley arm 28 is provided having at one extremity a peripherally grooved roller 29 for engaging the trolley wire, and at the other extremity affixed to but insulated from casing 7. This trolley arm is provided toward the point of attachment with an equivalent of a universal 85 joint 30, and embracing this joint, and attached at either side of the joint to adjacent portions of the arm is a spring 31. By this construction, the roller is maintained in engagement with the wire and at the same 90 time is permitted free lateral and vertical movement to compensate for slight variations in the relative position of the wire and the track rail.

The trolley arm 28 is further provided 95 with a suitable conductor connected to one terminal of the motor and the other terminal of the motor is grounded on to case 7, track rail 2 being used in this instance as a return conductor.

A switch may be inserted at any convenient point in the motor circuit to interrupt the latter when desirable, and a rheostat or similar device may be provided for convenience in stopping and starting the 105 motor.

While I have here shown and described a preferred form of my invention, for purposes of illustration, such embodiment is not to be interpreted as in any way limiting the 110 spirit and scope of the invention, such limitation being confined to that indicated in the accompanying claims.

What I claim:

1. In a carrier, a motor, a drive shaft, connecting means between said motor and said drive shaft, a wheel adjacent each extremity of said shaft, a gear on each wheel, a gear slidably mounted on each end of said shaft, and means for simultaneously moving one of said gears on said shaft into engagement with the gear on a respective wheel and moving the other gear on the shaft out of engagement with the gear on the respective wheel; said gears on the shaft arranged for reversely rotating the respective wheels.

2. In a carrier, a motor, a shaft adapted to be rotated by said motor, a wheel adjacent each end of said shaft, means on one end of

said shaft for rotating the corresponding wheel, means on the other end of said shaft for reversely rotating the other wheel, a pivoted lever having lateral extensions, and
5 links between said extensions and said rotating means, said links and said lever adapted to render operative one rotating means in one position of the lever, and to render operative the other rotating means in
10 the other position of the lever, and further adapted to render inoperative both rotating means in a third position of the lever.

3. A carrier driving mechanism comprising a drive shaft, means for rotating said
15 shaft, a wheel adjacent each end of said shaft, a clutch element on each wheel, a

clutch element slidably mounted on each end of said shaft for engagement with the clutch element on the corresponding wheel, a pivoted lever having lateral extensions, and link 20 means connecting an outer portion of each extension with one of said clutch elements on the shaft, said link means and lateral extensions so arranged that in a movement of the lever to engage a clutch element on the 25 shaft with a clutch element on a wheel the corresponding link will move toward a position of alinement with the pivoted end of the lever and the particular clutch element on the shaft.

30 In testimony whereof I affix my signature.

FLOYD E. PERKINS.
